ENGINE SPEED GOVERNING DEVICE

Charles H. Frick, Pontiac, and Ralph J. Rays, Dearborn, Mich., assignors to General Motors Corporation, Detroit, Mich., a corporation of Delaware

Application October 15, 1952, Serial No. 314,868

7 Claims. (Cl. 123—103)

This invention relates to internal combustion engines and particularly speed governors therefor operatively controlling the fuel supply to the engine.

The present invention has as its principal object to improve the speed governing devices disclosed in the United States patent application Serial No. 157,556 of Charles E. Ervin, Jr., filed April 22, 1950, now Patent No. 2,617,396. In the use of the aforementioned Ervin governing device it has been found that the speed control of the engine is not as stable as is desired, particularly under conditions of high speed, part throttle operation. These difficulties have been overcome in accordance with our invention which provides for the movement of the engine speed responsive diaphragm member to be transmitted to the fuel control rod through the control rod operating lever at a moment arm which increases at a substantially constant rate during its movement in the speed increasing or fuel decreasing direction, and also by arranging the connection between the lever and the rod so as to obtain a decreasing ratio of rod to diaphragm movement in the upper approximate half of the governed load range.

The means by which these and other improvements are effected will be readily understood from the following description of our invention, having reference to the drawings illustrating a specific embodiment wherein:

Figure 1 is a fragmentary elevational view of an internal combustion engine incorporating our improved speed governing device, with parts broken away and in section.

Figure 2 is an enlarged fragmentary view similar to Figure 1 with additional parts broken away and in section to better illustrate the improved speed governing device.

Figure 3 is a view in plan of the elements shown in Figure 2.

Figure 4 is a sectional view taken substantially on line 4—4 of Figure 2.

The engine as best shown in Figure 1 and indicated by the numeral 1 receives its combustion supporting air through an intake duct 2 controlled by a throttle valve 3 suitably operable by an accelerator pedal 4 through a linkage system 6, 7, 8 and 9. The duct 2 contains an auxiliary air intake passage 11 not controlled by the throttle valve 3, which is preferably of venturi shape whose throat 12 is tapped by a vacuum line 13, 14 leading to one end of a cylinder 16 in which is mounted a piston member 17 shown in the form of a flexible diaphragm (Figure 2).

The fuel is supplied to the engine by one or more injector devices 18 whose delivery rate is controllable by a longitudinally reciprocable regulator member shown as a rod 21 which is suitably guided for movement on the cylinder head 22 of the engine. Shown in Figure 1 is a rocker shaft 23 on which are journaled engine driven rockers, one of which is shown at 24 for operating the fuel injectors 18.

Linkage means 26, 27 operatively associated with the throttle valve control linkage 7—9 is also shown for effecting rotation of a shaft 28 in response to movement of the accelerator pedal 4. Mounted on and rotatable with the shaft 28 is a manual fuel control arm 29 carrying a pin 31 and an idler buffer spring 32 which operate to abut the arms 33 and 34 respectively of a fuel regulator control lever 36. The idler buffer spring 32 corresponds in function to the idler buffer spring 77 shown and described in the aforesaid Ervin application

in tending to rotate the control lever 36 in a counterclockwise direction about its pivotal axis defined by the shaft 37, and the pin 31 provides a one way driving connection between the arm 29 and the arm 33 for effecting opposite rotation of the control lever about its pivotal axis. The control lever 36 is biased to rotate in a counterclockwise direction about the axis of the shaft 37 by a torsion spring 38 which is shown suitably coiled about the shaft 37 and having the spring ends anchored to the arm 33 and to the bracket 39 in which the shaft 37 is journaled. The link 26 carries a pin 41 which travels on a cam surface 42 of the link 7, whereby depression of the accelerator pedal 4 causes the link 26 to move in a generally downward direction, rotating the link 27, shaft 28 and arm 29 in a clockwise direction and permits the control lever to rotate in a counterclockwise direction about the axis of its shaft 37. The arm 33 of the control lever 36 has a slot 40 in which a pin 45 on the fuel regulator rod 21 to the right in response to counterclockwise rotation of the control lever 36 results in increasing the fuel delivery rate of the injectors 18, and movement of this rod in the opposite direction results in decreasing the fuel delivery rate. In the position of the parts as shown the pin 41 on the link 26 is releasably engaged in an idler speed notch 43 at the upper end of the cam surface 42, and the buffer spring 32 effects a biasing action on the control lever arm 34 tending to rotate the control lever in the counterclockwise or fuel increasing direction. Also in this position of the parts as shown the pin 31 on the arm 29 is out of abutting engagement with the side of the control lever arm 33. Also, in the position of the parts as shown the engine throttle valve is closed, and substantially all of the combustion air for supporting engine operation at idle speed is constrained to pass through the venturi passage 11. The relatively high velocity of air flow through this venturi effects a high vacuum on the right hand side of the diaphragm 17, tending to move this diaphragm to the right as viewed in Figure 2. The opposite side of the diaphragm within the cylinder 16 is subject to atmospheric pressure, and the resultant force thereof acting on the diaphragm is employed for opposing counterclockwise rotation of the control lever 36 under the biasing action of the torsion spring and the idler buffer spring 32.

For transmitting this diaphragm force to the control lever, a drum-like member 44 is mounted rigidly to the control lever for rotation therewith about the axis of the control lever shaft 37. This drum member 44 provides a cylindrical cam surface 46 whose axis is eccentric to the axis of the shaft 37, and partially wrapped about this cylindrical surface of the drum member is a flexible ribbon-like member or band 47 whose opposite ends are anchored for movement with the drum member and the diaphragm 17 respectively. The connection of the band 47 to the drum member may be in the form of a simple stud or pin 48 projecting from the cylindrical surface 46 and extending through an opening provided thereto in the band member. At its opposite end the band has a U-shaped strap 49 riveted thereto which journals on and has a certain degree of lost motion with the end 51 of a safety link 52, which in turn journals in a clevis 53 riveted as at 54 to the diaphragm. The opposite end of the safety link 52 is hooked to a tab 56 projecting from the control lever 36 as best shown in Figure 4.

As will best be seen in Figure 2, the eccentricity of the cylindrical cam surface 46 with respect to the axis of the control lever shaft 37 is such that the cylindrical axis of the cam surface is disposed on the opposite side of the axis of the shaft 37 from the diaphragm 17 whereby the effective moment arm of the control lever acted upon by the diaphragm increases at substantially a constant rate as the control lever is moved in a clockwise direction from its engine full fuel position to decrease the engine fuel supply in response to increasing engine speed. As a result, the movement of the control lever toward a decreased fuel setting (in response to increasing engine speed movement of the diaphragm) is

uniformly accelerated and the tendency of the governor to stabilize engine speed is enhanced.

Upon manually advancing the engine speed by depression of the accelerator pedal 4, the pin 41 on the link 26 rides up out of the notch 43 on the cam surface 42 and thence travels downwardly on this cam surface 42 to cause clockwise rotation of the arm 29, with the result that the control lever rotates counterclockwise about the axis of the shaft 37 under the biasing action of the torsion spring 38 and shifts the fuel regulator rod 21 to the right in the direction of increased fuel delivery. The movement of the fuel regulator rod in response to the pivoting movement of the control lever is effected by the cam action of the control lever slot 40 on pin 45 of the fuel regulator rod. A curvature, as shown, has been added to the lower end of the slot 40 in order that the linear velocity of movement of the fuel regulator rod relative to the angular velocity of the control lever movement will be decreased in the upper half of the governed load range. As a result, the aforesaid constant rate of change in moment arm length between the diaphragm and the control lever is rendered more effective in stabilizing the engine speed, particularly under conditions of part throttle operation.

While it is appreciated that various minor changes or alterations in the construction and relation of the parts will readily suggest themselves to persons skilled in the art, such changes shall not depart from the spirit and scope of the invention which is set forth in the following claims.

We claim:

1. In an engine speed governing device having a piston member responsive to engine intake vacuum and a reciprocably guided fuel regulating member controlled thereby, linkage means operatively connecting said members including a lever supported for pivotal movement about an axis, a drum member rigid with the lever and provided with a cylindrical surface having its axis eccentric to the pivotal axis of the lever, a flexible strap wrapped about and anchored at one end to said cylindrical surface and anchored at its other end to the piston member, said lever having a slotted arm slidably embracing a pin on the fuel regulating member.

2. In an engine speed governing device having a first reciprocable member movable in one direction in response to increased engine intake vacuum and a second reciprocable member movable in said one direction to increase engine fuel supply and in the opposite direction to decrease said supply, linkage means for translating movement of said first member in said one direction into movement of said second member in the said opposite direction including a lever having a fixed axis of pivotal movement, a cylindrical cam surface on the lever having its axis eccentric to said axis of pivotal movement, and a tension link having one end anchored to said cam surface and its other end anchored to reciprocate with said first member, said lever having a pin and slot driving connection with said second member.

3. In an engine speed governor, a piston member responsive to engine intake vacuum, a reciprocably guided fuel control rod carrying a transversely disposed driving pin, a lever mounted for pivotal movement about an axis parallel to and laterally spaced from said pin, said lever having an arcuate slot slidably embracing said pin and a cylindrical cam surface eccentric with said axis, and a flexible link interconnecting said lever and piston member and wrapped about at least a portion of said cam surface.

4. In an engine speed governor having a reciprocably guided fuel supply regulator movable in the direction to decrease the fuel supply by a piston member responsive to increasing engine speed, linkage means for translating increasing engine speed movements of the piston member into fuel decreasing movements of the regulator including a pin carried by and disposed transversely to the reciprocatory path of the regulator, a lever mounted for pivotal movement about an axis parallel to and spaced from said pin, said lever having a surface in slid-

able driving engagement with said pin and curved in the direction of decreasing fuel movement of the regulator, a cam surface on the lever having a curvature of varying radius from said pivotal axis, and a tension link having one end anchored to the piston member and its other end wrapped about said cam surface and anchored to the lever.

5. In an engine speed governing device having a piston member, actuating means effective at a predetermined engine speed for moving the piston member in one direction including means forming a restricted engine air inlet and a fluid connection subjecting one side of the piston to the pressure within said inlet, a reciprocably guided engine fuel supply regulator, a pivoted lever for moving said regulator in the direction to decrease the fuel supply in response to movement of the piston member by said actuating means, and a resilient member for yieldably opposing said piston actuated movement of the regulator by the lever and for moving the regulator in the opposite direction when said actuating means is ineffective, the improvement consisting of a connection between the lever and piston member whose lineal distance from the lever fulcrum decreases at a substantially constant rate as the regulator is moved in the direction to decrease the fuel supply, and a connection between the lever and regulator in the form of a pin on the regulator and a curved camming surface thereon on the lever the radius of curvature of which surface decreases progressively to maintain a substantially linear relationship between piston movement and regulator movement.

6. In an engine speed governing device, the combination with a slidably reciprocal rod controlling the fuel supply to the engine, a pivoted lever having an arm slotted to slidably embrace a projection on said rod, a support providing a fixed axis for pivotal movement of the lever at a distance along said arm from the rod and a reciprocable member movable in one direction in response to increased engine speed for effecting pivotal movement of the lever in the direction to slidably drive said rod toward a decreased fuel supply position, of a connecting linkage between said members providing a moment arm for said reciprocal member relative to the pivotal axis of the lever which increases at constant rate during movement of the reciprocal member in said one direction, said connection including a flexible member and cylindrical cam, said cam being fixed to the lever and having its cylindrical axis eccentric with the lever pivotal axis, said flexible member being connected at one end to said reciprocal member and having its other end extending around said cam and movable with the lever about the lever axis.

7. In an engine speed governing device having a reciprocable rod controlling the engine fuel supply, a reciprocable member for adjustably moving said rod toward a decreased fuel setting in response to increasing engine speed, and a pivoted lever for transmitting decreasing engine speed movements of said reciprocable member to said rod, said lever having a moving connection with said reciprocable member whose distance from the pivotal axis of the lever increases at a substantially constant rate during movement of the lever in the decreasing fuel direction and having a moving connection with said rod whose lineal velocities of movement about the pivotal axis of the lever and longitudinally of the rod are substantially constant throughout the operable range of pivotal movement of the lever.
